(57) **CLAIM**

We claim the ornamental design for a work light, as shown and described.

DESCRIPTION

FIG. 1 is a top perspective view of the work light showing our new design.

FIG. 2 is a bottom back facing perspective view thereof.

FIG. 3 is a top perspective view thereof with the light panel tilted at an angle.

FIG. 4 is a top view thereof.

FIG. 5 is a bottom view thereof.

FIG. 6 is a left side view thereof.

FIG. 7 is a right side view thereof.

FIG. 8 is a front facing view thereof; and,

FIG. 9 is a back facing view thereof.

The broken line showing in FIG. 9 is for environmental purposes only. All other broken lines show portions of the article which form no part of the claimed design.

1 Claim, 7 Drawing Sheets

FIG. 1

FIG. 2

FIG. 3

FIG. 4

FIG. 5

FIG. 7

FIG. 6
